LOCK CONSTRUCTION

Henry F. Keil, Scarsdale, N. Y., assignor to
 Francis Keil & Son, Inc., a corporation of New
 York

Application June 13, 1934, Serial No. 730,417

16 Claims. (Cl. 70—47)

This invention relates to lock construction and more particularly to the key-controlled or key-operated portion of a lock mechanism.

One of the objects of this invention is to provide a practical, inexpensive and dependable key-controlled lock mechanism. Another object is to provide a mechanism of the above-mentioned character that will be capable of great ease of disassembly or assembly, as for purposes of repair, change of the combination to meet a different shape of key, or the like. Another object is to provide a construction of the above-mentioned character in which certain of the tumbler pins and/or coacting devices may be easily and conveniently held against disassembly or against falling out while permitting the disassembly from the lock construction of the parts of the latter. Another object is to provide a lock mechanism of the above-mentioned nature which will greatly facilitate and lessen the labor on the part of the locksmith in fitting a key to the lock or in performing other operations, such as changing the lock or tumbler arrangement so as to adapt the lock mechanism to another key, or for purposes of repair, or the like. Another object, also, is to provide a tumbler type of lock mechanism which will be of thoroughly reliable and dependable action in practical use and which in particular will be capable, in a simple and inexpensive manner, of resisting tampering or unauthorized efforts to manipulate it. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown a preferred form of my invention,

Figure 1 is a vertical central sectional view through the assembled key-controlled mechanism, showing the mechanism as related to a door and appropriate bolt or latch mechanism.

Figure 2 is a view, as seen from the right in Figure 1, certain parts being omitted;

Figure 3 is a transverse sectional view, as seen along the line 3—3 of Figure 1;

Figure 4 is a transverse sectional view, as seen along the line 4—4 of Figure 1;

Figure 5 is a vertical central sectional view of a portion of the lock construction of Figure 1, showing such portion detached from the door and illustrating the construction and action of certain features of my invention;

Figure 6 is a vertical central sectional view of the key plug or barrel, as removed from the cylinder or casing, and

Figure 7 is an enlarged view of certain portions of Figure 4.

Similar reference characters refer to similar parts throughout the several views of the drawing.

Referring now to the drawing, and more particularly to Figure 1, I have generally indicated at 10 a door, or the like, which has secured to it and carries a suitable casing 11 having therein any suitable form of bolt, or the like, and bolt-operating mechanism, the bolt being adapted to coact with a suitable keeper. The bolt mechanism 11 is to be operated by a key-controlled mechanism constructed in accordance with my invention.

Accordingly, I provide a casing or cylinder housing generally indicated at 12 preferably in the form of a solid casting suitably shaped to provide a substantially cylindrical lower portion 13 (Figures 1 and 3) and an upwardly and lengthwise extending portion 14, these portions being conveniently and preferably cast as a unit or integrally with a front or escutcheon plate 15 (Figures 1 and 2), the latter being preferably circular.

The cylinder portion 13 is bored out as at 16 (Figure 3) to rotatably receive the cylinder core or key plug 17 (Figure 1), the bore 16 being counterbored at the front or right-hand end thereof (see Figure 1) and hence in the front plate 15, as at 18, in order thereby to receive, and form a shoulder or abutment for the front peripheral flange 17a (Figure 1) of the key plug 17, movement of the latter in a direction toward the left as viewed in Figure 1 being thereby limited.

At its left-hand end, as viewed in Figure 1, the key plug 17, preferably projecting beyond the left-hand face of the cylinder housing 12, has detachably secured thereto, as by any suitable means generally indicated at 19, a connecting or operating bar 20 which is to enter the casing of the bolt mechanism 11 for coaction with and operation of the latter under the control of the key plug 17.

Any suitable means may be employed to relate the key-controlled parts 12—17 to the door 10 and hence to the bolt mechanism 11; for example, the door 10 may be provided with a hole 10a of sufficient size to receive the casing 12; front flange 15 of the latter abutting against the right-hand face of the door 10; the housing 12 is provided with ears 21—22 (Figure 3) projecting laterally

therefrom and having threaded holes therein for receiving screws 23 (Figure 1) which pass, excepting for their heads, through a plate 24 resting against or secured to the left-hand face of the door 10, screws 23, in coaction with the back plate 24 and the front flange 15 acting to clamp the door 10 therebetween and thus securely hold the parts in the hole 10^a in the door. Back plate 24 is, of course, provided with a suitable hole 24^a 10 to permit the passage therethrough of the operating bar 20.

Considering now the interrelation between the plug casing 12 and the key plug 17, it is first to be noted that the casing 12 is provided with a suitable number, illustratively five, of tumbler-receiving recesses indicated in Figure 1 at 31, 32, 33, 34 and 35, these recesses preferably being cylindrical and either cast or formed by drilling, extending downwardly and opening into the bore 16 and extending upwardly into the above-described portion 14 (see Figures 4 and 1) of the housing structure 12. Slidably fitted or mounted in these tumbler-receiving recesses are cylindrical tumblers, sometimes called pins, indicated in Figure 1 at 41, 42, 43, 44 and 45, these tumbler pins being preferably of the same length and being urged downwardly, as viewed in Figure 1, by springs 51, 52, 53, 54 and 55, the upper ends of the springs abutting against the upper closing 30 wall of the tumbler-receiving recesses.

These springs and tumblers may be inserted into their respective recesses in any suitable manner; for example, the upper ends of the recesses, as formed in the portion 14 of the casing 12 (Figure 4) may be open so that the tumblers may first be dropped in and then the springs inserted whereupon the upper open ends of the recesses may be closed in any suitable way as, for example, by a closure plate 36 which extends lengthwise 40 along the top of the casing portion 14 (Figure 1) in a guideway 14^a (Figure 4) extending between upstanding ribs or flanges 14^b and 14^c which may, after the closure plate 36 has been put in place, be bent or pressed over, as indicated in Figure 4, 45 to clamp and hold the closure plate 36 in place.

The rotatable key plug 17 is provided with a key slot 17^b extending lengthwise thereof, preferably throughout the lower portion of the key plug, as is better shown in Figure 3, and the vertical cross-section of the key slot 17^b may be given any desired shape or form; illustratively, it may have a shape like that shown in Figure 3, being thus provided with longitudinally extending ribs 17^c and 17^d.

The key plug 17 is also provided with tumbler-receiving recesses which, when the plug 17 is in the position shown in Figures 1 and 3, assumed to be the normal position, register with the tumbler-receiving recesses 31, 32, 33, 34, and 35 in the casing 12 and are the same in number, these respectively registering recesses being indicated in Figure 1 at 61, 62, 63, 64 and 65. The latter, also, are of the same cross-section as the former recesses so that, when the two sets of recesses are aligned, the tumblers 41, 42, 43, etc. pressed downwardly by their respective springs, emerge from their recesses 31, 32, 33, etc., respectively, and enter into the key plug recesses 61, 62, 63, etc., respectively, to an extent determined by the lengths of tumblers 71, 72, 73, 74 and 75, respectively, carried in the tumbler-receiving recesses of the key plug.

In Figure 1 the tumblers 71, 72, 73, etc. are shown of varying or differing lengths, and hence the upper tumblers 41, 42, 43, etc., project into

the key plug recesses, thus preventing rotation of the key plug 17 until a properly shaped key, shaped not only to enter the key slot 17^b (Figure 3) but also to have a suitably serrated or notched edge, raises all of the tumblers, each pair or set to such an extent that the upper tumblers 41, 42, etc. are just lifted sufficiently to be moved out of the key plug recesses, whereupon the key plug 17 may be rotated by the key and hence the bolt mechanism 11 (Figure 1) actuated.

The lowermost position of the tumbler pins 71, 72, 73, etc. may be determined in any suitable manner as, for example, by the vertical depth (see Figure 1) of the recesses 61, 62, 63, etc. in which they are respectively received, these recesses being formed in any suitable manner as by drilling or even casting, as by die casting; preferably these recesses are of the same depth and as indicated in Figures 1 and 4, they may terminate at about one of the ribs, such as rib 17^d of the key slot 17^b. Still assuming the parts to be in normal or locked position, as shown in Figures 1 and 4, I provide downward extensions of the tumbler recesses 61, 62, 63, 64 and 65 in the key plug, but these extensions, shown in Figure 1 at 81, 82, 83, 84 and 85, respectively, formed as by drilling or in the process of die casting, are of smaller cross-section or lesser diameter than the recesses 61, 62, 63, etc.; thus these extensions 81, 82, 83, etc. provide, with the tumbler-receiving recesses 61, 62, 63, etc., respectively, a clear passage diametrically through the key plug 17 but because the lower portions or extensions 81, 82, etc. are smaller in cross-section than the recesses 61, 62, etc., respectively, the tumblers or pins 71, 72, etc., do not enter these smaller recesses or extensions 81, 82, etc., respectively, but the latter are available for a purpose about to be described in detail.

Additionally, it is to be noted and as is shown in Figures 1 and 4, and still assuming the parts to be in normal or locked position, as in Figure 1, the lower wall of the cylindrical casing portion 13 is provided with apertures 91, 92, 93, 94 and 95, which are aligned and mate with the recess extensions 81, 82, 83, etc., respectively, thus making the latter accessible from the exterior of the casing 12. Furthermore, and as better appears in Figures 1 and 3, I provide a passage or hole 13^a extending from front to rear of the casing 12 and intersecting the tumbler-receiving recesses 31, 32, 33, etc., in the latter; this passage 13^a is closely spaced to the wall of the bore 16 in which the key plug 17 rotates (see Figure 3), it is exposed at the rear or left-hand end of the casing 12 (see Figure 1) but is normally covered up at the right-hand or front end of the casing 12 by the flange 17^a of the key plug 17.

Considering these features of my invention, let it now be assumed that it is desired or necessary to fit a key to the lock mechanism or to change the latter so as to require a differently serrated or notched key. In accordance with heretofore known practice, such a procedure involves a difficult and troublesome task in that the lock mechanism has to be taken entirely apart, the numerous parts thereof, most of them relatively minute, spill or scatter and become mixed up or confused, and disregarding whatever changes have to be made in the tumblers there results time-and patience-consuming operation in endeavoring to get the parts assembled again. But such detriments as these I effectively eliminate and avoid and accordingly, assuming that the mechanism is now removed from the door 10, thus making available the rear exposed end of the pas-

sage 13^a I insert into the latter a wire or pin-like member 37 (see now Figure 5), the pin 37 abutting against the upper tumbler 41; but thereupon I insert a pin-like member or wire 38 (Figure 5) in the aperture 91 and thus into the extension 81 of tumbler recess 61 in the key plug 17 and by then slowly pushing up on the pin 38, I move the tumblers 71 and 41 upwardly until their juncture comes into alinement with the inner end of pin 37, which may thereupon be pushed further to the right in between tumbler pins 41 and 71, closing the tumbler recess 31, and continuing through the passage 13^a through the wall intervening tumbler recesses 31 and 32, thus abutting the pin 37 against tumbler pin 42. The pin 38 is thereupon removed from aperture 91 and is inserted into aperture 92 and thus into the extension 82 of the tumbler recess 62 in the key plug 17, engaging the tumbler pin 72 in the latter, and then by pushing slowly upwardly on the pin 38, tumblers 72 and 42 are lifted to bring their junction in line with the right-hand end of the pin 37 which may thereupon be moved one step further toward the right in between the tumblers 42 and 72, and then onto the next tumbler arrangement, and so on, all the way through whatever number of tumbler recesses with tumblers that there might be in the lock construction, the pin 37 finally abutting against the flange 17^a of the key plug 17.

Having thus inserted the pin 37, all of the tumblers 41, 42, 43, etc., with their respective springs are imprisoned within their respective tumbler recesses, being held against spilling or emergence therefrom by the pin 37. The key plug 17 may then be withdrawn from the casing 12 and the locksmith may do whatever is necessary with respect to the latter and its tumbler pins.

For example, if it is necessary to fit a key, he may then notch or cut a key blank appropriately, being guided by the vertical dimensions of the tumbler pins 71, 72, 73, 74 and 75 as to the contour to be given the key, thus tumbler pins being easily removable and easily replaceable, once the key plug 17 has been removed.

Or, to make the lock mechanism respond to a different shape of key, he may interchange the existing tumbler pins 71, 72, 73, etc., or he may provide an entire new series of such pins and an appropriately contoured key. For example, also, while the key plug 17 is thus still out of the casing 12, the locksmith may insert into the key slot 17^b a notched or coded key, then drop appropriate tumblers in the tumbler recesses 61, 62, 63, etc., and file off or otherwise remove such portions of the thus inserted tumblers as project beyond the periphery of the key plug 17. These or like operations completed and the upper tumbler pins 41, 42, etc., being still held uppermost by the still inserted pin or wire 37, the key plug 17 is reinserted into the bore 16, from the right, as viewed in Figures 1 and 5, flange 17^a of the key plug again fitting into the counterbore 18 and covering up the right-hand end of the passage 13^a, whereupon the pin 37 may be withdrawn, thus to release the tumbler pins 41, 42, etc. under the action of their respective springs and thus freeing them for co-action with the key plug. The operating bar 20 is again attached to the left or rear end of the key plug 17 by the means 19 above mentioned, the latter again preventing withdrawal of the key plug 17 from its bore 16, and thus the mech-

anism may be restored or again mounted in the door 10.

It will be understood, also, that, if desired, the pin 37 may be associated with the casing 12 to hold the tumblers within the latter, during various steps of manufacture or assembly of the lock construction in the factory. It will also be understood, in so far as certain features of my invention are concerned, the locksmith or operator may successively advance the retaining pin 37 under the upper tumblers by lifting the latter with the lower tumblers (the ones in the key plug 17) by means other than the implement or pin or wire 38 inserted successively through the recess extensions 91, 92, 93, etc.; for example, an implement may be inserted into the key slot 17^b suitably shaped or constructed to reach into the key slot to engage first the tumbler pin 71 (Figures 1 and 5) and lift the latter and hence its associated upper tumbler, advance the pin 37, then by this implement lift the next tumbler 72, and so on. In any event, it will be seen that I am enabled in a rapid and thoroughly dependable manner to greatly facilitate disassembly, assembly, and particularly assembly succeeding disassembly as is so frequently the case in the hands of a locksmith.

I have above pointed out how, after manipulating the successive pairs of tumblers and inserting the pin 37 (Figure 5) the upper tumblers 41, 42, 43, etc. are imprisoned, being held disengaged from the key plug or barrel 17 and that thereafter the latter may be withdrawn; preferably I also provide against spilling or disassembly of the tumblers 71, 72, 73, etc. from the key plug and in that connection reference may again be made to Figure 5.

Hence, referring to Figure 5, I provide, in the key plug 17, a passage 17^a extending parallel to the axis of the key plug 17 and adjacent the periphery of the latter and in a line such that the passage 17^a, commencing at the rear or left-hand face of the plug 17, intersects all of the tumbler recesses 61, 62, 63, 64 and 65 in the key plug 17, preferably adjacent the upper ends of the latter. The passage 17^a, however and preferably, terminates in back of the front or right-hand face of the key plug 17, being thus accessible only from the rear end of the plug.

With no key in the key slot 17^b, the tumblers 71, 72, 73, etc. bottom in their respective recesses, the upper ends of the tumbler pins thus falling at or below the line of the passage 17^a. Accordingly, after having inserted the pin 37 in the passage 13^a as above described, a pin or wire-like member 50 (see now Figure 6) is inserted into the passage 17^a so that it extends across all of the otherwise open ends of the tumbler-receiving recesses 61, 62, 63, etc., thus closing these recesses and imprisoning the tumblers 71, 72, 73, etc. within their respective recesses. It is at this point, then, after thus having inserted the pin or wire 50, that the key plug 17 is withdrawn from the casing 12 as above described, appearing when thus withdrawn as shown in Figure 6.

Thus, spilling of these tumblers from their recess is dependably precluded, and this feature is of particular advantage and importance where the tumblers in the key plug are of a composite construction and take the form better shown in Figure 4 and presently to be described in detail. Accordingly, unintentional removal of the pin tumblers and related parts from the key barrel is dependably prevented, confusion or mixing up of the pin tumblers precluded, and great con-

venience and speed of handling, whether in course of manufacture or in course of subsequent disassembly for repair, replacement, or change, brought about.

5 Thus, the disassembly and assembly are greatly facilitated and much annoyance and many time-consuming manipulations are dependably eliminated. At the same time, however, another feature of my invention comes into play; as indicated above, the several pairs of tumbler pins may, in so far as the above-described features of my invention are concerned, be of any desired or suitable construction or shape and preferably are solid but where these pairs of tumbler pins 10 are solid, there may be some element of danger or risk involved due to the generally remote possibility, usually depending upon the range of change of vertical dimension of the tumbler pins 15 in the key plug, of surreptitiously causing the tumbler pins to be raised sufficiently to permit rotation of the key plug 17 by applying to the assembled and installed lock mechanism, as to the front or escutcheon plate 15 thereof, any suitable mechanism that will subject the lock 20 mechanism to rapid and powerful vibration. For example, an electric motor-driven vibrator, attached or applied to the front of the casing 13 subjects the latter and particularly the generally loosely mounted tumbler pins to rapid vibration, 25 causing the tumbler pins to vibrate up and down in their respective recesses and thereby bringing about such a lifting thereof that, at an appropriately awaited stage of the vibration, all of the tumbler pins are appropriately lifted or aligned to permit freedom of rotation of the key 30 plug 17 relative to the casing 12. In accordance with my invention, I dependably guard against such possible unauthorized or keyless actuation of the lock mechanism.

40 Accordingly, and as is better shown in Figure 4, all or a suitable number of the tumbler pins in the key plug 17 are substantially cup-shaped, as is better shown in Figure 4 or, where they are cylindrical, they or a suitable number thereof 45 are counterbored from the top. In Figure 4, and, on a larger scale, in Figure 7 tumbler 71 is shown thus counterbored as at 71^a. Into this counterbore 71^a is an auxiliary pin 39 whose length is such, better shown in Figure 7, that its upper end 50 and the upper end of the tumbler pin 71 lie in substantially the same plane; its diameter is greater than the diameter of the aperture 91 in the wall of the bore 16 or in the casing portion 13 so that, should the key plug 17, under the 55 control of a key or otherwise, be rotated through 180°, as it normally is in normal operation, the pin 39 will not fall out of either the main tumbler 71 or through the aperture 91.

The upper tumbler 41 with which the lower 60 tumbler 71 coacts may be made tubular, as shown in Figure 7 and in Figure 4, and its inside diameter is sufficiently greater than the diameter of the auxiliary pin 39 so that the latter may easily enter the tubular tumbler 41.

65 In normal or locked position of the parts, the relation therebetween is as shown in Figure 4 (see also Figure 7). The auxiliary pin 39 is virtually completely housed within the main tumbler pin 71, and the same relation of parts 70 exists with respect to such other or others of the pairs of tumbler pins as are selected to be thus constructed. As thus constructed, the operation thereof under the control of a proper key is as already above described.

75 However, should the key-controlled mechanism

be subjected to vibration of the character above described, thereby to cause the various pairs or sets of tumbler pins to vibrate or jump up and down in their recesses in the effort to bring about such forced or vibrating withdrawal of the upper tumbler pins 41, 42, 43 etc. into their recesses and thereby permit unauthorized vibration of the key plug 17, the same vibration becomes effective to cause the auxiliary pin 39 (Figure 4) to vibrate or to jump up and down relative to the tumbler pin 71 itself, thus bringing the auxiliary tumbler pin 39 up into the upper tumbler 41 and thus virtually telescopically making a unit out of the upper tumbler 41 and the lower tumbler 71, a unit that is not separable, so long as the auxiliary pin 39 continues to vibrate, by relative movement between the two tumblers in a transverse direction.

Thus, even if the vibration were effective to bring about an adequate withdrawal of the upper 20 tumblers 41, 42, etc., to permit rotation of the key plug 17, the same vibration is effective to keep the auxiliary pin 39 of the lower tumbler 71 (and the pins of such other of the lower tumblers as are similarly constructed) interengaged with the upper tumbler in such a way as to prevent the kind of transverse relative movement therebetween or between the pin 39 and the upper tumbler recess 31 as is necessary to permit free rotation of the key plug 17.

30 The disassembly and reassembly of the construction where one or more of the pairs of tumbler pins have the features just above described and shown in Figure 4 proceeds substantially as earlier above described in detail but it is to be 35 pointed out that the cup-shaped character of the lower tumbler pin 71 exposes the bottom or end wall thereof to the action of the pin 38 (Figure 5) that is used to raise the tumblers, and thus pin 38 raises not only the cup-shaped tumbler 40 71 itself but also its auxiliary pin 39 as well.

Thus, there has been provided in this invention a key-controlled lock construction in which the various objects hereinbefore set forth together with many thoroughly practical advantages are successfully achieved. It will be seen that the construction and arrangement are of a thoroughly practical character and are thus well adapted to meet the varying conditions of hard practical use. Moreover, it will be seen that the 50 construction is capable of ready embodiment in practical form, is inexpensive, and makes for great major saving and great convenience in practice.

As many possible embodiments may be made 55 of the above invention and as many changes might be made in the embodiment above set forth, it is to be understood that all matter hereinbefore set forth or shown in the accompanying drawing is to be interpreted as illustrative and 60 not in a limiting sense.

I claim:

1. In lock construction, in combination, a key plug having a longitudinally extending key-receiving slot and having a plurality of radially extending tumbler-receiving recesses communicating with said key slot, tumblers within said recesses, said recesses having extensions through to the other side of said key plug, thereby to expose said tumblers to the action of a device 70 inserted in the plug through said extensions, a casing having a bore in which said key plug is movably received, said casing having a plurality of tumbler-receiving recesses with spring-pressed tumblers therein, one for each of the tumblers 75

in said key plug, said casing having a passage accessible from the rear thereof and extending parallel to said bore and adjacent to the wall thereof and intersecting the tumbler-receiving recesses in said casing, said casing having a plurality of apertures through the wall of said bore juxtaposed to and aligned with said recess extensions in said plug, whereby, by inserting a tool successively through said apertures and recess extensions, the pairs of tumblers may be successively lifted and another tool, inserted in said passage, may be successively moved along the latter underneath the casing tumblers, thereby to retain all of the casing tumblers within their recesses during and after the removal of the key plug from the casing.

2. In lock construction, in combination, a key plug having a longitudinally extending key-receiving slot and having a radially extending tumbler-receiving recess communicating with said slot, a tumbler within said recess, a casing in which said key slot, a tumbler within said recess for actuation by a key inserted in said slot, said recess having an extension through to the other side of said key plug, thereby to expose the tumbler to the action of a device inserted in the plug through said extension, a casing having a bore in which said key plug is movably received and having a tumbler-receiving recess, a tumbler in said last-mentioned recess, a spring in said last-mentioned recess for coaction with said second-mentioned tumbler to cause the latter to coact with the tumbler recess in said key plug and with the tumbler in the latter, said spring tending to push said second-mentioned tumbler in a direction into said bore, said casing having a passage intersecting said second-mentioned tumbler-receiving recess adjacent the end thereof nearest said bore and having an aperture through the wall of said bore juxtaposed to and aligned with the recess extension in said plug, whereby upon inserting a tool through said aperture and recess extension, the two tumblers may be lifted against the action of said spring and another tool, inserted in said passage, may be moved along the latter and underneath said second-mentioned tumbler, thereby to retain the latter with its spring in its recess during and after removal of the key plug from the casing.

3. In lock construction, in combination, a key plug having a longitudinally extending key-receiving slot and a radially extending tumbler-receiving recess communicating with said slot, a tumbler within said recess, a casing having a bore in which said key plug is movably supported, said casing having means communicating with said bore for slidably guiding a tumbler in a direction toward or away from the axis of said key plug, a tumbler in said guiding means for coaction with said tumbler recess and said first-mentioned tumbler, spring means acting upon said second-mentioned tumbler and urging the latter along said guiding means and in a direction toward the axis of said key plug, and means within said casing and positioned on that side of the wall of said bore remote from said key plug for accommodating tool means for holding said second-mentioned tumbler against movement under the action of its spring thereby to prevent said tumbler, in the absence of said key plug, from being pushed out of its guiding means by its spring.

4. In lock construction, in combination, a key plug having a longitudinally extending key-receiving slot and a radially extending tumbler-receiving recess communicating with said slot, a tumbler within said recess, a casing in which said

key plug is movably supported, said casing having means for slidably guiding a tumbler in a direction toward or away from the axis of said key plug, a tumbler in said guiding means for coaction with said tumbler recess and said first-mentioned tumbler, spring means acting upon said second-mentioned tumbler and urging the latter along said guiding means and in a direction toward the axis of said key plug, said casing having a passage leading to said guiding means whereby, after lifting both of said tumblers against the action of said spring, a tool inserted through said passage may be positioned underneath said second-mentioned tumbler to limit the movement thereof under the urge of the spring. 15

5. In lock construction, in combination, a key plug having a longitudinally extending key-receiving slot and a radially extending tumbler-receiving recess communicating with said slot, a tumbler within said recess, a casing in which said key plug is movably supported, said casing having means for slidably guiding a tumbler in a direction toward or away from the axis of said key plug, a tumbler in said guiding means for coaction with said tumbler recess and said first-mentioned tumbler, spring means acting upon said second-mentioned tumbler and urging the latter along said guiding means and in a direction toward the axis of said key plug, said key plug having a peripheral flange at its front end and said casing having a counterbore in its front wall into which said key plug peripheral flange is received, said casing having a passage extending substantially parallel to the axis of said key plug from the rear of said casing, thence intersecting said guiding means, and then terminating in a face of said counterbore, whereby upon lifting said tumblers against the urge of said spring a tool may be inserted through said passage and in between said two tumblers, thereby to hold said second-mentioned tumbler against coaction with said key plug and to permit removal of the latter, the peripheral flange of said key plug covering up the front terminus of said passage. 30

6. In lock construction, in combination, a key 45

plug having a longitudinally extending key-receiving slot and a radially extending tumbler-receiving recess communicating with said slot, a tumbler within said recess, a casing in which said key plug is movably supported, said casing having means for slidably guiding a tumbler in a direction toward or away from the axis of said key plug, a tumbler in said guiding means for coaction with said tumbler recess and said first-mentioned tumbler, spring means acting upon said second-mentioned tumbler and urging the latter along said guiding means and in a direction toward the axis of said key plug, said key plug having a peripheral flange at its front end and said casing having a counterbore in its front wall into 50

which said key plug peripheral flange is received, said casing having a passage extending substantially parallel to the axis of said key plug from the rear of said casing, thence intersecting said guiding means, and then terminating in a face of said counterbore, whereby upon lifting said tumblers against the urge of said spring a tool may be inserted through said passage and in between said two tumblers, and continued along said passage into said counterbore and against the peripheral flange of said plug, thereby to dislodge said plug axially from said casing and to prevent said casing, tumbler, and spring from falling out of said guideway. 65

7. In lock construction, in combination, a key 70

75

plug having a longitudinally extending key-receiving slot and having a plurality of radially extending tumbler-receiving recesses communicating with said key slot, tumblers within said recesses, a casing having a bore in which said key plug is movably received, said casing having a plurality of tumbler-receiving recesses with spring-pressed tumblers therein, one for each of the tumblers in said key plug, said casing having passage means extending into said second-mentioned tumbler-receiving recesses whereby, by inserting tool means through said passage means and upon lifting a pair of tumblers, said tool means may be moved underneath the casing tumblers, thereby to retain the latter with their springs within their recesses.

8. In lock construction, in combination, a key plug having a longitudinally extending key-receiving slot and having a plurality of radially extending tumbler-receiving recesses communicating with said key slot, tumblers within said recesses, a casing having a bore in which said key plug is movably received, said casing having a plurality of tumbler-receiving recesses with spring-pressed tumblers therein, one for each of the tumblers in said key plug, said casing having passage means accessible from a wall of the casing other than the front wall thereof and intersecting each of said second-mentioned tumbler-receiving recesses whereby, by inserting tool means into said passage means and successively lifting the pairs of tumblers, said tool means may be moved underneath the casing tumblers to restrain the latter from coaction with said key plug.

9. In lock construction, in combination, a key plug having a key-receiving slot and a radially extending tumbler-receiving recess communicating with the slot, a tumbler within said recess, a casing movably mounting said key plug and having a tumbler-receiving recess opening against the key plug and having a spring-pressed tumbler therein, said casing having a bore in which said key plug is received that is of a diameter substantially equal to the diameter of said key plug, thereby to form a direct bearing for said plug, and means forming a passage accessible from the exterior of the lock construction whereby tool means may be inserted and said casing tumbler may be receded by said tool means into its recess against the urge of its spring and held against coaction with said key plug, thereby to permit removal or assembly of the key plug and casing.

10. In lock construction, in combination, a key plug having a key-receiving slot and a radially extending tumbler-receiving recess, a cup-shaped tumbler within said recess, a pin within said cup-shaped tumbler and bottoming in the latter and terminating adjacent the open end thereof, and a casing movably receiving said key plug and having a tumbler-receiving recess opening against said key plug and having a hollow spring-pressed tumbler slidably mounted therein, said hollow tumbler being, when said key plug is in "locked" position, thereby juxtaposed to said cup-shaped tumbler and being capable of receiving said pin, whereby, upon said casing with the plug therein being subjected to vibration, said pin may oscillate between both of said tumblers.

11. In lock construction, in combination, a key plug having a key-receiving slot and a radially extending tumbler-receiving recess, a hollow tumbler within said recess, a casing movably receiving said key plug and having a tumbler-receiving recess opening against said key plug and

a hollow spring-pressed tumbler therein, and a plunger normally contained within said first-mentioned hollow tumbler but slideable relative thereto and capable, upon said casing and key plug being subjected to forced vibration, of oscillating within both tumblers when the latter are aligned.

12. In lock construction, in combination, a key plug having a key-receiving slot and a plurality of radially extending tumbler-receiving recesses communicating with said slot, tumblers within said recesses, a casing having a bore in which said key plug is movably received, said casing having a plurality of tumbler-receiving recesses opening into said bore with spring-pressed tumblers therein, one for each of the tumblers in said key plug, and adapted to be received within the recesses of the latter when said key plug is in "locked" position, at least one pair of said tumblers being hollow and having therein a single slideable member normally received within one of the tumblers, thereby not to interfere with the actuation of the tumblers and key plug under the control of a key but capable of oscillating between both of the tumblers and thereby preventing relative transverse movement thereof when the lock construction is subjected to forced vibration.

13. In lock construction, in combination, a key plug having a key-receiving slot and a plurality of radially extending tumbler-receiving recesses communicating with said slot, tumblers within said recesses, a casing having a bore in which said key plug is movably received, said casing having a plurality of tumbler-receiving recesses opening into said bore with spring-pressed tumblers therein, one for each of the tumblers in said key plug, and adapted to be received within the recesses of the latter when said key plug is in "locked" position, and means housed within one of said tumblers and responsive to forced vibration of said casing and plug for preventing relative movement therebetween even if said forced vibration achieves release of said key plug by said casing tumblers.

14. In lock construction, in combination, a key plug having a key-receiving slot and a plurality of radially extending tumbler-receiving recesses communicating with said slot, tumblers within said recesses, a casing having a bore in which said key plug is movably received and the surface of said bore forming a bearing for the outer surface of said key plug, said casing having a plurality of tumbler-receiving recesses opening into said bore with spring-pressed tumblers therein, one for each of the tumblers in said key plug, and adapted to be received within the recesses of the latter when said key plug is in "locked" position, said lock construction having passageway means for the reception of means capable, when actuated, of holding said second-mentioned tumblers against movement under the action of their respective springs, thereby to prevent said tumblers, in the absence of said key plug, from being pushed out of their respective recesses and to thereby permit withdrawal or inserting movement of said key plug relative to said casing, and for the reception of means capable, when actuated, of holding said first-mentioned tumblers within their respective recesses in said key plug so that, upon withdrawal or inserting movement of said key plug relative to said casing, said tumblers are retained within their respective recesses.

15. In lock construction, in combination, a key plug having a key-receiving slot and a plurality of radially extending tumbler-receiving recesses

- communicating with said slot, tumblers within said recesses, a casing having a bore in which said key plug is movably received, said casing having means with which said tumblers coat, and said plug having a passage extending from the rear face thereof substantially parallel to the axis of said plug and adjacent the periphery of the latter and intersecting all of said tumbler-receiving recesses whereby, upon the insertion of a member into said passage, the inserted member bridges across said tumbler-receiving recesses and prevents movement of the tumblers therein in a direction out of said recesses. 5
5. said key plug having passage means extending into said tumbler-receiving recesses whereby, by inserting tool means through said passage means, said tumbler-receiving recesses are closed against outward movement therefrom of said tumblers, 10 thereby to retain the latter assembled to said plug.
16. In lock construction, in combination, a key plug having a key-receiving slot and a plurality of radially extending tumbler-receiving recesses 15 communicating with said slot, tumblers within

HENRY F. KEIL.
